UNITED STATES PATENT OFFICE

119,201

DESIGN FOR AN ILLUMINATED TABLE VASE

Grant E. Bolton, Cleveland, Ohio

Application October 27, 1939, Serial No. 87,889

Term of patent 3½ years

To all whom it may concern:

Be it known that I, Grant E. Bolton, a citizen of the United States, residing in Cleveland, in the county of Cuyahoga and State of Ohio, have invented a new, original, and ornamental Design for an Illuminated Table Vase, of which the following is a specification, reference being had to the accompanying drawing, forming a part thereof.

Fig. 1 is an elevational view of the illuminated table vase showing my new design;

Fig. 2 is a plan view thereof.

I claim:

The ornamental design for an illuminated table vase, substantially as shown.

GRANT E. BOLTON.
